HIGH-EFFICIENCY MULTIVIBRATOR CIRCUITS

Cyril E. McClellan, Catonsville, Md., assignor to Westinghouse Electric Corporation, East Pittsburgh, Pa., a corporation of Pennsylvania

Application July 28, 1943, Serial No. 496,521

4 Claims. (Cl. 250—27)

1

My invention relates to electronic wave generators, and in particular relates to an electronic wave generator of the multivibrator type.

Multivibrator circuits have found an increasing use in the radio art in which current pulses of relatively short duration separated by a longer interval are generated. Such arrangements of the conventional type comprise two electronic tubes, one of which conducts current only while the current pulse is flowing, and the other of which conducts current during the longer interval between pulses. The current flow in the latter tube is thus very nearly continuous and represents a continued loss of power which may be hundreds of times greater than the power put into the useful pulses. Hence such an arrangement is, in reality, highly inefficient from an electrical power standpoint.

The objects of my invention are to provide an arrangement for using electronic tubes to generate pulses of substantially the above-described type and which comprises two tubes, but in which both tubes are extinguished except during the relatively short time of the current pulse.

Another object of my invention is to provide an arrangement in which current through the tubes between the anodes and cathodes is limited only by the electron emission of the cathode itself.

Another object of my invention is to provide a multivibrator in which tubes of a given current and voltage rating permit a much larger useful output of power than is the case with conventional multivibrators of the prior art.

A still further object of my invention is to provide an electronic pulse generator which permits a greatly increased efficiency and large saving of power wasted in conventional multivibrators now known.

Other objects of my invention will become apparent upon reading the following description taken in connection with the drawing in which the single figure is a diagrammatic showing of a circuit embodying the principles of my invention.

Referring particularly to the drawing, a pair of grid-controlled electronic tubes 1 and 2, which may be of the high vacuum type, are supplied with direct current energy from a positive terminal 3 of a direct current voltage source. The anode of the tube 1 is connected directly to the terminal 3, while the anode of the tube 2 is connected to the terminal 3 through a resistor 4. The cathode of the tube 2 is connected to ground through the primary 6, a resistor 7 and a secondary 8 of a transformer having close coupling between its windings 6 and 8. The terminal of the

2

resistor 7 which is adjacent the primary winding 6 is connected through a capacitor 9 to the control electrode of the tube 1. The control electrode of the tube 1 is likewise connected through a resistor 11 to the terminal 12 of a source of bias voltage of which the other terminal is grounded. The terminal 12 is further connected through a resistor 13 to the control electrode of the tube 2. The last-mentioned control electrode is connected through a capacitor 14 to one terminal of an input circuit of which the other terminal is grounded. The common terminal of the resistor 13 and the control electrode of the tube 2 is connected through a capacitor 15 with the cathode of the tube 1. A load circuit may have one of its terminals connected to the cathode of the tube 1, its other terminal being grounded; alternatively, a load circuit may have one terminal connected to the anode of the tube 2, its other terminal being grounded.

The windings 6 and 8 are preferably wound on a magnetic core to produce a maximum of coupling between them. They may alternatively be referred to as constituting a double-winding transmission choke coil such as is described and shown as windings 31 and 32 in Fig. 2 of my Patent No. 2,379,168, for Thermionic tube circuits, issued June 26, 1945, and assigned to the assignee of this present application. The polarity of the windings 6 and 8 is such that a current flowing from the cathode of tube 2 to ground will produce opposing magnetic effects on the magnetic core as it flows through the two windings.

The mode of operation of the above-described arrangement is as follows: The value of the bias voltage impressed by the source 12 on the control electrodes is made such that when no current is flowing through the resistors 7 and 5, the tubes 1 and 2 are both biased to cut off current flow from their anodes to their cathodes. If, now, a positive pulse of voltage is impressed through the capacitor 14 on the control electrode of tube 2, the latter tube begins to conduct current through resistor 4, windings 6 and 8, and resistor 7. The voltage drop through the resistor 7 momentarily imparts a positive pulse of voltage through capacitor 9 on the control electrode of tube 1. Tube 1 thereupon begins to conduct current and impress very nearly the entire voltage of the source 3 across the resistor 5. If a load circuit is connected in shunt with the resistor 5, this voltage is accordingly impressed on the load. The output voltage of the tube 1 appearing across the resistor 5 acts through the condenser 15 to impress a more positive voltage on the control

3

electrode of tube 2, thereby tending to increase the current flow from the anode to the cathode of the latter. This in turn impresses a more strongly positive voltage pulse on the resistor 7, which, acting through the condenser 9, makes the grid of the tube 1 more strongly positive. The current from anode to cathode in both tubes thus rises rapidly until it equals the full electronic emission of their respective cathodes. However, the condensers 9 and 15 soon acquire 10 saturating charges which prevent them from continuing to impress the positive voltages present across the terminals of resistors 5 and 7, respectively, on the control electrodes of tubes 2 and 1. Thereupon, the current flow from anode to cathode of these two tubes begins to decrease. When this happens the decreased voltages across resistors 5 and 7 are impressed on the control grids of tubes 1 and 2 by means of condensers 9 and 15, thereby impressing negative voltage pulses 20 on the control electrodes of the tubes 1 and 2. These control electrodes thus react to further and more rapidly decrease the current flow from anodes to cathodes of the tubes 1 and 2 with the result that current flow through both of these 25 tubes quickly falls to zero, if the positive signal voltage impressed through capacitor 14 on the control of electrode of tube 2 has ceased. The tubes 1 and 2 then remain nonconductive until the capacitor 14 on the input circuit impressed 30 another positive voltage pulse on the control electrode of tube 2.

If desired, the load circuit may be connected from the anode of the tube 2 to ground instead of between the cathode of tube 1 and ground, in which case its polarity is the reverse of the polarity with the last-mentioned connection.

While I have described one specific embodiment of the principles of my invention, it is of broader application in ways which will be evident to those skilled in the art.

I claim as my invention:

1. An impulse generator comprising a first grid controlled electron tube having its anode connected directly to the positive terminal of a direct current voltage source and its cathode connected to the negative terminal of said source through an impedance, a second grid controlled electronic tube having its anode connected to the positive terminal of said source through an impedance and a cathode connected to the negative terminal of said source through a pair of closely coupled windings, and a second impedance, the control electrode of the first said tube being connected to the end of the last-mentioned impedance which is closer to the cathode of the second-mentioned tube, the other end of the last-mentioned impedance being connected to the cathode of the first-mentioned tube, the control electrode of the second-mentioned tube being connected through a capacitor to the cathode of the first-mentioned tube, a resistor connected between the control electrodes of said tubes, a source of bias voltage connected to an intermediate point on the last-mentioned resistor, and means for impressing a signal on the control electrode of the second-mentioned tube.

2. An impulse generator comprising a first grid controlled electron tube having its anode connected directly to the positive terminal of a direct current voltage source and its cathode connected to the negative terminal of said source through an impedance, a second grid controlled electronic tube having its anode connected to the

4

positive terminal of said source through an impedance and a cathode connected to the negative terminal of said source through a pair of closely coupled windings, the polarity of said windings being such that current flowing from the cathode of the second-mentioned tube to the negative terminal of said source will produce opposing magnetic effects in said winding, and a second impedance, the control electrode of the first said tube being connected to the end of the last-mentioned impedance which is closer to the cathode of the second-mentioned tube, the other end of the last-mentioned impedance being connected to the cathode of the first-mentioned tube, the control electrode of the second-mentioned tube being connected through a capacitor to the cathode of the first-mentioned tube, a resistor connected between the control electrodes of said tubes, a source of bias voltage connected to an intermediate point on the last-mentioned resistor, and means for impressing a signal on the control electrode of the second-mentioned tube.

3. An impulse generator comprising a first grid controlled electron tube having its anode connected directly to the positive terminal of a direct current voltage source and its cathode connected to the negative terminal of said source through a resistor, a second grid controlled electronic tube having its anode connected to the positive terminal of said source through a resistor and a cathode connected to the negative terminal of said source through a pair of closely coupled windings, and a second resistor, the control electrode of the first said tube being connected to the end of the last-mentioned resistor which is closer to the cathode of the second-mentioned tube, the other end of the last-mentioned resistor being connected to the cathode of the first-mentioned tube, the control electrode of the second-mentioned tube being connected through a capacitor to the cathode of the first-mentioned tube, a resistor connected between the control electrodes of said tubes, a source of bias voltage connected to an intermediate point on the last-mentioned resistor, and means for impressing a signal on the control electrode of the second-mentioned tube.

4. An impulse generator comprising a first grid controlled electron tube having its anode connected directly to the positive terminal of a direct current voltage source and its cathode connected to the negative terminal of said source through a resistor, a second grid controlled electronic tube having its anode connected to the positive terminal of said source through a resistor and a cathode connected to the negative terminal of said source through a pair of closely coupled windings, the polarity of said windings being such that current flowing from the cathode of the second-mentioned tube to the negative terminal of said source will produce opposing magnetic effects in said winding, and a second resistor, the control electrode of the first said tube being connected to the end of the last-mentioned resistor which is closer to the cathode of the second-mentioned tube, the other end of the last-mentioned resistor being connected to the cathode of the first-mentioned tube, the control electrode of the second-mentioned tube being connected through a capacitor to the cathode of the first-mentioned tube, a resistor connected between the control electrodes of said tubes, a source of bias voltage connected to an intermediate point on the last-mentioned re-

sistor, and means for impressing a signal on the control electrode of the second-mentioned tube.
